ANGULAR TAP CLAMP FOR FEED LINES

Robert A. Becker, Sr., and Stephen P. Becker,
Poughkeepsie, N. Y.

Application January 28, 1933, Serial No. 653,956

1 Claim. (Cl. 173—273)

This invention relates to a feed line clamp of that class which is used in electrical installations where it is desired to tap a feed wire and secure a lead wire or wires thereto by mechanical means.

While there are devices for the purpose of tapping a feed wire and securing thereto a small lead wire, as I have shown in my applications for patents, as follows—Serial No. 483,494, filed, Sept. 22, 1930 issued Oct. 24, 1933 as Patent No. 1,932,009; Serial No. 577,741, filed, November 28, 1931 issued Oct. 24, 1933 as Patent No. 1,932,010, and Serial No. 602,835, filed, March 29, 1932 issued Mar. 13, 1934 as Patent No. 1,950,771, none of these devices are so constructed as to be adapted to heavy work, such as taking a large lead wire off of a large feed wire.

The object of the present invention is to provide a clamp for this purpose that shall be strong, durable and efficient, contain few parts and be easily attached to the wires.

Another object of the invention is to provide a clamp of this kind that shall be easily tapered and covered after being installed in place.

A further object of the invention is to provide a clamp having a single body member and a series of clamping jaws mounted therein, both for holding the feed wire and the lead or leads.

With these and other objects in view, my invention consists in certain novel construction and combination of parts as will hereinafter be fully described and claimed, and illustrated in the accompanying drawing, which forms a part hereof and in which like figures of reference refer to corresponding parts in all of the views, and it is understood that slight changes may be made without departing from the spirit of the invention.

In the drawing—

Figure 1 shows a top plan view of the clamp.

Figure 2 shows an elevation of the feed wire end, with one of the jaws slightly open.

Figure 3 shows an elevation of the side, or lead clamping side with one jaw slightly open.

Figure 4 shows an end view of the lead clamping end.

Figure 5 shows a bottom plan view of a modified form of the clamp where two lead clamps are employed at an angle to each other and to the feed clamp, and it is to be understood that the lead clamp may be formed at any desired angle to the feed wire clamp, and that any suitable number may be employed.

Referring to Figures 1, 2, 3 and 4, of the drawing, the device comprises a body member 10, formed with the groove 11 for the feed wire 12,

and the groove 13 for the lead wire 14 at right angles to the feed wire.

The body member 10, adjacent the groove 11 is formed with the stationary jaw members 15 which are formed with an angular jaw edge 16 and a lip 17; and slightly to the rear of the groove 11 is formed the guideway 18 for the movable tongue 19 of the jaw members 20; said tongue 19 being provided with a threaded hole for the locking bolt 21, which is passed through the guideway 18 and threaded into the tongue 19, for the purpose of drawing the jaws together in clamping position upon the wire.

The object of the beveled or angular edge 16 is to prevent the jumping out or accidental removal of a small wire, should several wires be held within the same jaws, and the lip 17 also tends to keep the opening between the jaw faces closed to retain the wires within.

To the rear of the feed wire clamping jaws 15 and 20, and at an angle thereto are formed the stationary jaw members for the tap or lead wire 14, and these stationary jaws 40 are also formed with guideways 23 extending therethrough, for the movable clamping jaws 24 which are mounted 25 therein and which are formed with the tongues 25 and the threaded hole for the clamping bolt 26. The movable jaws 20 and 24 are in fact interchangeable.

In the modified form shown in Figure 5, the device comprises the body member 30, having the stationary jaws 31 for the feed line 12, and the two angular tap line portions 33 formed with stationary jaws 34 for the lead wire 14 and both the feed line and the lead line portions are supplied with the movable clamping jaws 36, secured in place by the clamping screws 37 and the washers 38.

The construction of the jaws in this modification being the same as in that shown in Figures 1, 2, 3 and 4, they require no further detail description.

It is understood that the lead line clamps may be of any number desired and extend at an angle from the feed line clamp portion of the device.

It will also be seen by the drawing that the shape of the device is such that after being installed, that it may be readily insulated by the usual taping.

Having thus described my invention, what I claim as new and desire to secure by Letters Patent, is—

A clamp for the purpose specified comprising a body having at least two fixed jaws thereon, and slidible jaws co-operating therewith, said jaws

having conductor receiving grooves in their opposed faces, the grooves of one set of jaws being disposed at right angles to the grooves of the other set, each jaw having its front face formed with an edge inclined in a direction parallel with the longitudinal axis of the conductor groove and a lip extending from the narrow portion of the front face immediately back of the inclined portion, each of said lips being movable into overlapping relationship with the wider portion of the front face of the other jaw upon movement

of the slideable jaws towards the fixed jaws to prevent displacement of relatively small conductors from the grooves at times when the inclined edges are in non-contacting relationship, and means carried by the body and engageable with the sliding jaws to move the latter toward the fixed jaws, and to clamp the conductors in the grooves. 5
